UNITED STATES PATENT OFFICE.

HOBART FREIBURGHOUSE, OF GOFF, KANSAS.

TIMER.

Application filed November 2, 1922. Serial No. 598,463.

To all whom it may concern:

Be it known that I, HOBART FREIBURGHOUSE, a citizen of the United States, residing at Goff, in the county of Nemaha and 5 State of Kansas, have invented certain new and useful Improvements in Timers, of which the following is a specification.

The primary object of the present invention resides in the provision of an improved 10 form of timer adapted for specific application to Ford automobiles for overcoming the necessity of providing the usual spark coil for each cylinder, it being well known in this type of motor vehicle a spark coil 15 is employed for each cylinder for building up the current between the magneto or battery and the contact points of the timer, insuring what is usually termed a "hot spark."

20 A still further object of the present invention is the provision of such a timer that is simple in operation and comparatively inexpensive of manufacture and a timer that when once installed is not liable to readily 25 become out of order.

With the above and other objects in view as the nature of the invention will be better understood by reference to the accompanying drawings forming part of the present 30 application, the same consist of the combination and arrangement of parts hereinafter more fully described.

In the accompanying drawings, wherein like reference characters indicate corresponding parts throughout the several views:—

Figure 1 is a front elevational view of the timer casing clearly disclosing the spaced contact points arranged therein, and also 40 setting forth an additional contact point, centrally disposed within the timer, and constructed in accordance with the present invention.

Figure 2 is a cross sectional view upon the 45 line 2—2 of Figure 1.

Figure 3 is a view similar to Figure 2, but disclosing in addition to this figure, the rotating contact arm positioned upon the usual rotary shaft.

50 Figure 4 is a fragmentary side elevational view of the rotating contact member, a portion of the same being shown in cross section, disclosing its connection to the rotary shaft, and

55 Figure 5 is a diagrammatic view of the electrical wiring system, employed by me in

the application of the present device to an internal combustion engine.

Referring to the several view, and particularly to Figures 1 to 3 inclusive, there 60 is disclosed a timer embodying the usual fiber casing 1, having a lining 2 arranged therein. This casing 1 has the usual internal equi-distantly spaced contact points 3, each of the same secured within the casing 65 by the post members 4, passing through suitable openings in the lining 2, and casing to be there secured by the binding nuts 5.

Centrally disposed within the casing 1, and spaced inwardly of the rear wall thereof, is an annular shaped metallic disk 6, this disk is rigidly positioned within the casing by a screw threaded bolt member 7 formed upon the disk and extending outwardly of the casing as shown in Figures 2 and 3. 75

Extending within the casing as in the latter mentioned figure, is the outer end of the cam shaft 8, reduced and screw threaded at its extreme end portion 9 for screw threaded engagement within a screw threaded bore 10, of a fiber block 11. Suitably secured to this fiber block is the usual metallic arm 12, carrying a roller contact 13 for engagement with spaced stationary contacts 3, within the casing 1 when the cam shaft 8 is rotated. 80

Extending relative sensitive helical spring 14, adapted to have its free projecting end 14' 90 contacting with the annular disk 6 of the casing 1 as clearly shown in Figure 3. Conveniently supported upon the upper longitudinal surface of the fiber block 11 is a flat-like metallic arm 15 having its outer 95 end 15' curved downwardly for contact with one of the convolutes of the above mentioned coil spring 14. This metallic arm 15 may be secured to the fiber block by a set screw or the like having a knurled 100 annular head 16.

In the diagrammatic view, Figure 5, the stationary contact points 3 are shown as being electrically connected to the several spark plugs 17 of an internal combustion engine by electric wires A, the said spark plugs being suitably grounded as at 18 to the vehicle frame. The flat-like contact disk 6 in the casing 1 is connected through the instrumentality of the binding post 7, 110 with one end of a high tension wire b from the single spark coil c, this coil also

being grounded to the frame of the vehicle as at *d*. The said spark coil *c* is also in circuit with the usual magneto *E* found in Ford automobiles.

In the operation of the device, the rotary contact roller 13 having continuous electrical connection with the spark coil *c* through the high tension wire *b*, annular disk 6, within the casing 1, sensitive spring 14 and metallic arm 15, it will be readily understood that the current from the high tension wire is carried by the spring 14 to the roller 13 which makes contact with the stationary points 3, each of which is connected to its appropriate plug 17, for firing these plugs in each cylinder at the predetermined time as is now the case with the conventional form of timer.

While the form of the invention herein shown and described is what is believed to be the preferred embodiment thereof, it is nevertheless to be understood that various forms, modifications and arrangements of

the parts may be made without departing from the spirit and scope of the invention 25 as claimed.

What I claim as new is:—

A timer comprising a shell, a lining of insulating material located therein, a plurality of spaced contacts passing transversely through the shell and lining, a block mounted for rotation in the shell, a brush carried by the block for successive engagement with the contacts, a bar arranged within the lining, a binding post 30 connected with the bar and passing through the lining and shell, a coil spring 35 interposed between the bar and the block and connected with the bar, and a conductor mounted upon the block and having an angularly disposed end portion which engages the convolution of the coil springs.

In testimony whereof I affix my signature.

HOBART FREIBURGHOUSE.
